UNITED STATES PATENT OFFICE.

OTIS WM. DODGE, OF PORT EDWARDS, WISCONSIN.

DRYING-CYLINDER FOR PAPER-MAKING MACHINES.

977,376.

Specification of Letters Patent. Patented Nov. 29, 1910.

Application filed March 11, 1910. Serial No. 548,658.

To all whom it may concern:

Be it known that I, OTIS WM. DODGE, of Port Edwards, in the county of Wood and State of Wisconsin, have invented certain new and useful Improvements in Drying-Cylinders for Paper-Making Machines; and I hereby declare that the following is a full, clear, and exact description thereof, reference being had to the accompanying drawings, which form part of this specification.

This invention relates to so-called "drying cylinders" for paper making and other machines, in which the material is dried by passing it over steam heated cylinders; and the object of this invention is to provide efficient means for withdrawing the water of condensation from such cylinders thoroughly and effectively. In Fourdrinier paper machines where the matted pulp to be dried is very wet, a great deal of steam is condensed in the cylinders, and the efficiency of such cylinders is greatly impaired if the water of condensation remains therein. And also a great amount of steam is wasted by contact with the water of condensation and much heat is lost by the water of condensation adhering to the walls of the cylinder. Various attempts have been made to remove the water of condensation from such cylinders and the object of my invention is to accomplish the removal of all water of condensation quickly and effectively, thereby economizing the steam and greatly increasing the efficiency of such cylinder.

My invention therefore consists in the novel means for removing water of condensation from such drying cylinders, and will be readily comprehended upon reading the following description and by reference to the accompanying drawings, in which I have illustrated several embodiments of the invention as applied to a drying cylinder. And I will summarize in the claims the features of the invention for which protection is desired.

In said drawings—Figure 1 is a longitudinal section through a conventional form of drying cylinder showing one embodiment of the invention. Fig. 2 is an enlarged transverse section on line 2—2, Fig. 1, showing the scoop in different positions by the aid of dotted lines; and Fig. 3 is a similar section on line 3—3, Fig. 1. Fig. 4 is a longitudinal section of another embodiment of the invention; and Fig. 5 is a cross section

on line 5—5, Fig. 4. Fig. 6 is a longitudinal section of a cylinder showing another embodiment of the invention; and Fig. 7 is a cross section on line 7—7, Fig. 6.

In the drawings, 1 designates a drying cylinder which may be of any desired kind, and is usually constructed of some sheet metal that is a good conductor of heat, and mounted upon hollow trunnions 1^a, 1^b. Arranged axially of and within said cylinder is a drain pipe 2 which may extend through either trunnion; but—as shown in Fig. 1—it is closed at the end next trunnion 1^a and extends through trunnion 1^b, and may be connected outside the trunnion 1^b by means of a suitable rotary stuffing box 2^a to a drain pipe 2^b, as shown. Steam can be admitted to the cylinder 1 through either one of these hollow trunnions and exhausted through the other. In the latter case steam might be conducted through the trunnion 1^a and exhausted through the trunnion 1^b, in which case the drain pipe 2 could discharge into the exhaust pipe. The arrangement of the steam inlet and exhaust pipes and their connections to the cylinder 1 forms no part of the present invention and therefore it is unnecessary to illustrate same; nor is it necessary to illustrate the discharge connections of the pipe 2^b outside the cylinder as this will vary according to the construction of the machine in which the drying cylinder is employed, and the steam connections therewith, it only being essential that the pipe 2 shall discharge the water of condensation conducted therewith outside of the cylinder 1.

Attached to the inner wall of the cylinder and extending longitudinally thereof, is a scoop 3, which is preferably formed of a strip of sheet metal bent in U-shape; one side of said scoop being attached to the inner wall of the cylinder as shown in Figs. 1 and 2, in any suitable way, so as to make a close joint therewith at its edge; and the mouth of said scoop opening in the direction of rotation of the cylinder, so that as the scoop rotates, with the cylinder, it will pick up all the water in the cylinder. The scoop is preferably provided at suitable intervals with pockets 3^a in its bottom or rear side, and these pockets in turn are connected with the pipe 2 by means of pipes 2^a, which are preferably bent on a convolute curve as shown, so that as the scoop rises at the ascending side of the cylinder the water will

flow from the pockets 3^a into pipes 2^a and pass therethrough into the drain pipe 2 during the rotation of the cylinder.

As shown in Fig. 2 the bends 2^b of the pipes 2^a adjacent the drain pipe 2 may be such that the water will be trapped in the bends 2^b as the scoop rises and some water will be retained in the bends 2^b and discharged therefrom into pipe 2 as the scoop descends. Thus the water may be discharging all the time through the pipes 2^a into the pipe 2, and the bends therein prevent any water draining back from the pipe 2 into the trough 3 when the latter comes below the level of the drain pipe 2. I may make some of the pipes 2^a with different bends. As shown in Fig. 1 every other pipe 2^a has a full convolution, the bend being extended beyond the bend 2^b, as shown at 2^c, so as to connect with the pipe 2 at the side thereof directly adjacent the scoop 3 (see Fig. 3), while the bends 2^b connect with the pipe 2 at the side opposite the scoop 3 (see Fig. 2). In other words it might be said that the pipes having the bends 2^b make a half turn around the drain pipe 2 while the pipes having the bends 2^b, 2^c, make a full turn around the drain pipe 2. In this construction the pipes will not all discharge simultaneously and equally into the drain pipe 2, as the pipes having the bends 2^c will discharge into the pipe 2 practically alternately with the pipe having the bends 2^b, which will prevent any such accumulation of water in, or sudden discharge of water into the pipe 2, as might choke the latter or cause water to back up into the pipes 2^a and discharge back into the cylinder. As the scoop 3 extends the length of the cylinder it will be obvious that all water of condensation in the cylinder will be picked up and discharged through the pipe 2. The cylinders are sometimes made so long that it is necessary to employ internal annular braces to stiffen them; and my invention is especially adapted thereto as the scoop can be made practically continuous, intermediate the braces, or even pass therethrough as desired.

If the cylinder is of very large diameter or the condensation therein is very great, a plurality of scoops may be used. In Figs. 4 and 5 two diametrically opposite scoops 3 are shown within the cylinder, each connected to the central drain pipe 2 by pipes 2^a. As shown in Fig. 4 the pipe 2 need not necessarily be one continuous pipe but could be made up of a series of pipe sections suitably united.

Of course one of the features of the invention is to provide for removing the water of condensation simultaneously substantially along the entire length of the cylinder, by means of a scoop or series of scoops extending the length of the cylinder.

In place of one continuous metal scoop 3, as shown in Figs. 1 and 4, a series of short scoops 3^c may be arranged close together, and preferably in line, longitudinally of the cylinder, as shown in Figs. 6 and 7, each of 70 said short scoops being connected by a pipe 2^a with the central drain pipe 2.

While it would be possible to rotate the scoops within the cylinder, I prefer to have the scoops rotate with the cylinder, and 75 therefore to fasten the outside edges of the scoops to the inner wall of the cylinder as shown in the drawings. By reason of the curve in the pipes, as described, the scoop will be in position to begin to take up water, 80 before any water in the curved pipes or pipe 2 could return therefrom into the scoop, and therefore the water of condensation will always be discharged through the pipe 2.

The inner end of the pipe 2 may be either 85 directly supported in the stuffing box 1^a or on a bracket 1^b attached to the head of the cylinder as shown.

As the scoop travels with the drying shell it scoops water from the bottom of the cylinder and as it moves upward the water flows down through the curved pipes and is delivered into the drain pipe which in turn discharges the water out of the cylinder.

What I claim is:

1. In combination with a drying cylinder, an axially disposed drain pipe arranged within the cylinder and extending substantially the length thereof, scooping means within and extending longitudinally of the 90 cylinder, and convolutely bent pipes for conducting water from the scooping means into said drain pipe.

2. In combination with a drying cylinder, an axially disposed drain pipe arranged 105 within the cylinder and extending longitudinally thereof, scooping means extending longitudinally of the cylinder, and convolutely bent pipes for conducting water from the scooping means into said drain pipe, 110 some of the pipes having a greater convolute bend than others, whereby the time of discharge of said convolute pipes into the drain pipe is varied.

3. In combination with a drying cylinder, 115 scooping means attached to the inner wall of and extending substantially from end to end of the cylinder, a drain pipe extending axially of and substantially from end to end of the cylinder, and pipes connecting 120 said scoop with the drain pipe, said connecting pipes being bent on convolute curves, substantially as described.

4. In combination with a drying cylinder, a drain-pipe within the cylinder, a scoop extending longitudinally of the cylinder and provided with pockets, and convolutely bent pipes for conducting water from the scoop pockets into said drain-pipe.

5. In combination with a drying cylinder, 125

a longitudinally disposed scoop attached to the inner wall thereof and extending substantially from end to end of the cylinder, an axially disposed drain-pipe extending substantially from end to end of the cylinder, and convolutely bent pipes connecting said scoop with the drain-pipe.

6. In combination with a drying cylinder, longitudinally disposed scooping means attached to the inner wall thereof and extending substantially from end to end of the cylinder, an axially disposed drain pipe extending substantially from end to end of the cylinder, and convolutely bent pipes con-

necting said scooping means with the drain pipe, some of the connecting pipes having their convolutions of greater extent than that of the others to vary the time of discharge of the convolute pipes to the drain pipe.

In testimony that I claim the foregoing as my own, I affix my signature in presence of two witnesses.

OTIS WM. DODGE.
